UNITED STATES PATENT OFFICE

SYLVESTER M. VIELE, OF ALTOONA, PENNSYLVANIA

APPARATUS FOR MOUNTING WIRES

Application filed November 30, 1927. Serial No. 236,736.

This invention is especially designed for catenary supported trolley suspension, particularly such suspensions as are used in high speed railway practice. Such suspensions 5 have hitherto been made, as for instance in the patent to myself and Harvey K. Le Sure, No. 1,497,047, June 10, 1924. The structure shown in said patent is a desirable one except where increased lateral stability 10 and a vertical yielding support is desirable. The present invention contemplates a means for producing increased lateral stability against wind pressure by placing a compression member from the converging points of 15 the two lower suspenders to the messenger wire using the messenger wire as a base for the compression member. This, in a practical way, prevents side-sway because any side-sway through the compression member 20 would force a lifting of the messenger wire which is of sufficient weight to form a practically rigid base. While this structure prevents the side-sway it puts into the structure a rigidity at the point of support which is 25 detrimental and in accordance with the present invention there is a yielding support immediately below the compression member which gives some cushioning, or yielding, effect at this point directly to the trolley wire 30 supported. The invention also involves the arrangement of insulation for each individual trolley support between the immediate trolley support, or suspender, and the cross support carrying such suspender, particularly in connection with a rigid structure. Features and details of the invention will 35 appear more fully from the specification and claims.

40 A preferred embodiment of the invention is illustrated in the accompanying drawings as follows:—

Fig. 1 shows a perspective view of a track and trolley system therefor.

45 Fig. 2 an end view of the same.

Fig. 3 an enlarged view of the support and one of the suspenders.

Fig. 4 an enlarged view of a wire clamp for the yielding trolley connection.

Fig. 5 an alternative construction of suspender.

Fig. 6 an end view of a track system using the alternative form of suspender.

1 marks the track, and 2 supporting posts 55 at the sides of the track, these having the usual guy wires 3. A catenary 4 extends between the posts and this supports a supporting wire 5 through connections 6. Suspender connections 7 are arranged on the supporting wire, preferably under the connections 6. Suspender supports 9 are connected through insulators 8 with the connections 7. The suspender supports converge in a fitting 10 and a compression member 11, 60 ordinarily in the form of a tube, extends downwardly from the fitting 10 to the trolley supporting clamp 12. Inclined suspenders, or tension members, 13 extend from the clamp 12 to the ends of the suspender supports 9. 65

The clamp has the upper plate 14. This is provided with a socket 15 into which the compression member 11 extends, the compression member being clamped by a bolt 15^a. A lower plate 16 is secured in clamping relation to the plate 14 by U-bolts 17 which extend through the plates 14 and 16. Yielding trolley supporting wires 18 extend around the ends of the clamping plate 16 and are carried in between the plates 14 and 16, the plates 14 and 16 being faced to receive the wires 13 and 18 so that the single clamp secures all of them. 75

The wires 18 are carried so nearly horizontal as to prevent any lateral movement at their lower point. A U-bolt 19 straddles the wire 18 and extends through a plate 20 above the wires 18. This supports an auxiliary messenger wire 21. Connections 22 extend 85 90

from this auxiliary wire at intervals to a trolley wire 23 in the usual manner.

A messenger wire 24 extends through the fitting 10 and this forms a catenary which is 5 connected at intervals by uprights 21^a with the auxiliary messenger wire 21.

With this structure, it will be noted, that any side movement of the trolley is prevented through the rigidity of the compression member 10 acting upon a weighted and consequently substantially fixed base at the upper end of the compression member, the weight of the messenger wire at this point being ample for this purpose. The tension members may 15 be extended to both sides of the compression member to accomplish this purpose, or one inclined rigid member 25 may be used in connection with the compression member as illustrated in the alternative structure shown 20 in Figs. 5 and 6. In this structure the compression member 11 is connected through insulation 26 directly with the supporting wire and the rigid inclined member 25 is connected directly with the supporting wire through 25 insulations 27. In this case it will be seen that any tendency to side-sway will be resisted, in one direction the compression member 11 acting to receive the thrust and the member 25 operating as a tension member, 30 and in the opposite direction, the member 25 receiving the thrust and the member 11 operating as the tension member. In either case, however, there is for each strain a compression 35 member giving rigidity to the structure.

With a rigid compression member leading directly from the support and operating from a base formed by the messenger wire the trolley wire is given too great rigidity adjacent to the connection. This is obviated in the 40 present structure without a loss of rigidity against side-sway by the yielding support afforded through the wires 18. These permit of the limited vertical movement of the trolley wire and its auxiliary messenger wire 45 without any possibility of side movement.

What I claim as new is:—

1. In an apparatus for mounting wire, the combination of a cross member; a contact wire; an insulated laterally rigid frame-work 50 between the cross member and the contact wire; and a vertically yielding laterally rigid supporting connection between the contact wire and the frame-work.

2. In an apparatus for mounting wire, the 55 combination of a cross member; a contact wire; an insulated laterally rigid frame-work between the cross member and the contact wire; and a vertically yielding connection between the contact wire and the frame-work, 60 said yielding connection comprising inclined converging wires and a spreader at the bottom of the frame-work supporting said inclined wires.

3. In an apparatus for mounting wire, the 65 combination of a cross member; a contact

wire; an insulated laterally rigid frame-work between the cross member and the contact wire; a vertically yielding connection between the contact wire and the frame-work; and a clamp at the bottom of the frame-work forming a spreader and clamp for securing 70 said inclined wires.

4. In an apparatus for mounting wire, the combination of an electric contact wire; a catenary structure supporting the contact wire; a cross support; a laterally rigid insulated suspender extending downwardly from 75 said support; and yielding laterally and opposingly inclined connections between the contact wire and the suspender.

5. In an apparatus for mounting wire, the combination of a cross support; a contact wire; a laterally rigid suspender extending downwardly from the support comprising two suspender members converging toward a point of support, one of said members being a compression member; and a vertically yielding laterally rigid connection between the suspender and the contact wire. 85

6. In an apparatus for mounting wire, the combination of a cross support; a contact wire; a laterally rigid suspender extending downwardly from said support comprising a downwardly extending compression member; two side members converging toward a point of support toward the bottom of the compression member; and a vertically yielding laterally rigid connection between said suspender and the contact wire. 90

7. In an apparatus for mounting wire, the 100 combination of a cross support; a contact wire; a laterally rigid suspender extending downwardly from said support comprising a downwardly extending compression member; two side members converging toward a point of support toward the bottom of the compression member; and a vertically yielding connection between said suspender and the contact wire comprising inclined wires extending 105 from the contact wire and a spreader secured to the suspender carrying the inclined wires. 110

8. In an apparatus for mounting wire, the combination of an electric contact wire; a cross support; a laterally rigid suspender comprising a compression member; suspender wires at the side of the compression member converging toward a point at the bottom of the compression member; and a yielding connection between the contact wire and the suspender comprising inclined wires extending 115 from the contact wire and a clamp forming a spreader for the inclined wires and securing the suspender wires, said clamp being secured to the compression member. 120

9. In an apparatus for mounting wire, the combination of a cross support; a messenger wire suspended from said support; a laterally rigid suspender carried by the support comprising a compression member having a mes- 125

senger wire as a base; a contact wire; and a yielding connection between the compression member and the contact wire.

10. In an apparatus for mounting wire, the combination of a cross support; a contact wire; supporting wires having insulated connections with said cross support; a messenger wire carried by the supporting wires; a laterally rigid suspender carried by the supporting wires comprising a compression member extending downwardly from the supporting wires and having the messenger wire as a base; and a yielding connection between the compression member and the contact wire.

15. In testimony whereof I have hereunto set my hand.

SYLVESTER M. VIELE.
